ABSTRACT: In a contact arrangement for circuit breakers an elongated contact element is arranged resiliently in a contact element holder and provided at one end with a contact tip of arc-resistant contact metal. To attach the contact tip to the contact element, the contact tip is provided with an anchoring fin engaging in a groove in the contact element and projecting behind a supporting edge on the contact element holder.

ELECTRIC CONTACT MEANS

BACKGROUND OF THE INVENTION

1. Field of the Invention

In contact means which are intended to close and break high currents the contact elements are usually provided with a contact tip of arc-resistant contact metal, usually of copper-tungsten type. The purpose of the contact tip is to prevent scorch marks from appearing on the main contact surface of the contact element which normally consists of silver-plated or otherwise surface-treated copper, i.e. a material having good electrical conductivity but relatively little resistance to arcing. In order to fulfill this purpose the contact tip is placed so that the base points of an arc formed during short-circuiting or breaking arise on the tip and remain there.

2. The Prior Art

The most usual method of attaching the contact tip to the contact element is soldering, an attachment method requiring considerable time and thus making the contact means more expensive. The heating of the contact element required for the soldering also has the disadvantage that the copper becomes softer. This entails a greater risk that the contact element will bend, which may, cause the silver layer to flake off. Even from the point of view of mechanical wear a soft material is unsuitable for the contact element. Furthermore, if the soldering is not carried out carefully, there is a risk that the contact tip may loosen and cause considerable damage.

SUMMARY OF THE INVENTION

The object of the present invention is to provide a contact means in which the contact tip is fixed to the contact element in such a way that the above mentioned disadvantages with previously known contact means are avoided as far as possible. This is achieved according to the invention by providing the contact tip on the side of the tip facing away from the contact surface with a projecting anchoring fin which is arranged to engage like a hook in a groove in the contact element and to project behind a supporting edge of the contact element, said supporting edge being arranged at that end of the contact element which is situated nearest the contact tip. By attaching the contact tip in this way its manufacture is considerably simplified and an improvement in quality is obtained over the conventional soldering method since no damaging heating of the contact element is required.

The supporting edge arranged on the contact element holder is suitably designed to form a stop for the tip as well as for the movement of the contact element. Since the movement of the contact element is limited by the tip meeting the supporting edge, the contact force between the tip and the contact element is maintained even when one contact member of the contact means during a breaking process is at some distance from the other contact member and an arc exists so that the current flows through the tip to the contact element.

BRIEF DESCRIPTION OF THE DRAWINGS

The invention will be further described with reference to the accompanying drawings which show various embodiments of the invention. FIG. 1 shows in axial section a sheath contact means. FIGS. 2, 3 and 4 show three projections at right angles to each other of a contact tip in the contact means shown in FIG. 1. FIG. 5 shows a knife contact means and FIG. 6 a pressure contact means. Contact tips of the type shown in FIGS. 2-4 are also included in the contact means according to FIGS. 5 and 6.

DESCRIPTION OF THE PREFERRED EMBODIMENTS

The contact means shown in FIG. 1 comprises a stationary sheath contact 1 which cooperates with a movable contact plug 2. The sheath contact 1 has a plurality of elongated, axially arranged contact elements 3 of silver-plated copper arranged in ring formation inside a contact element holder 4. At its free end the contact element holder 4 supports an arcing

ring 5 of copper-tungsten. The contact element 3 is pressed radially inward with the help of helical springs 6 which, in the closed position of the contact means, effect the necessary pressure between the contact element 3 and the movable contact plug 2 and between the contact element 3 and a peg-shaped contact part 7 arranged at the bottom of the sheath contact. At its front end each contact element 3 is provided with a contact tip 8, shown in detail in FIGS. 2-4. The contact tip 8 is made of copper-tungsten and is sintered to its final shape. On the side of the tip 8 facing away from its contact surface 9 the tip is provided with a projecting anchoring fin 10. The fin 10 extends in the longitudinal direction of the contact element 3 beyond both ends of the tip so that two projections 11 and 12 are formed. In the contact element 3 is a recess 13 in the form of a transverse groove, open at the front, in which the tip 8 is inserted. The contact element 3 is also provided with a longitudinal groove 14 on its opposite side in which the fin 10 of the tip is guided. The backwardly directed projection 11 of the fin effects a grip which locks the rear end of the tip. The forwardly directed projection 12 of the tip abuts a supporting edge 15 on the arcing ring 5, which is designed so that the ring 5 prevents the tip 8 from tilting or gliding forwards.

When the movable contact plug 2 is in position to make contact and the tip 8 is to carry current, the contact surface between the tip 8 and the contact element 3 has the same contact force as the contact surface between the tip 8 and the movable contact plug 2. In completely closed position the current transmission takes place directly between the movable contact plug 2 and the copper contact element 3.

When the movable contact 2 during a breaking process is at some distance from the contact element an arc exists which carries current through the tip 8 to the contact element 3. Also in this case, therefore, sufficient contact force is required between the tip 8 and the contact element 3. This contact force is obtained since the stop between the tip 8 and the supporting edge 15 also provides a stop for the movement of the contact element 3. Hence, the spring force acting on the contact element 3 is transmitted to the tip 8.

FIG. 5 shows a knife contact means with a stationary clip-type contact 16 and a movable contact knife 17. The clip-type contact 16 has two or more contact elements 3 with contact tips 8, which are attached in the same way as in the arrangement according to FIG. 1. The contact elements 3 are arranged in a contact element holder 18 which is provided at the front with a supporting edge 19.

FIG. 6 shows a section through a pressure contact means which is rotationally symmetrical about the axis shown in dotted lines. The contact means comprises a number of contact elements 3 which are arranged in a stationary contact element holder 20. The movable contact member of the contact means consists of a contact sheath 21. The contact elements 3 are provided with contact tips 8 shaped and attached in the same way as described in connection with FIG. 1. The supporting edge of the contact element holder is in this case designated 22. At the rear side of the contact elements 3 a damping member has been arranged which consists of a plurality of rubber washers 23 and a curved pressure plate 24 to transfer the pressure between the contact elements 3 and the washers 23.

It is obvious from the embodiments shown that the invention can be used in several different contact means. However, the invention is not limited to the embodiments shown, but many modifications are feasible within the scope of the following claims. For example with a sheath contact according to FIG. 1, instead of the helical springs 6 leaf springs may be used which are designed so that they yield edgewise, in which case one and the same groove in the contact element 3 can be used both to retain the springs and to guide the contact tip 8.

I claim:

1. An electric contact means having two cooperating contact members, a contact element holder having an inwardly directed supporting edge, one of said contact members com-

prising at least one elongated contact element, said contact element movably mounted in said contact element holder and provided at one end with a contact tip of arc-resistant contact metal, said contact tip having a contact surface, means resiliently urging said contact element in the direction of said contact surface, said contact element having a groove therein, said contact tip provided with an anchoring fin projecting from that side of the contact tip facing away from its contact surface, said anchoring fin including hook means engaging in said groove in said contact element and a projection protecting behind said supporting edge on said contact element holder, said supporting edge arranged at that end of said contact holder which is situated nearest said contact tip.

2. Electric contact means according to claim 1, in which

said anchoring fin extends beyond both ends of said contact tip in the longitudinal direction of said contact element.

3. Electric contact means according to claim 1, in which said contact element has a recess therein in the side of said contact surface and said contact tip is arranged in said recess.

4. Electric contact means according to claim 1, in which said groove in the contact element extends in the longitudinal direction of said element and is situated in that side of the contact element which faces away from said contact surface.

10 5. Electric contact means according to claim 1, in which said supporting edge on said contact element holder forms a stop for the tip as well as for the movement of the contact element.
